W. L. GREENAWAY

REINFORCED TOOL HANDLE

Filed Dec. 30, 1925

Patented Oct. 12, 1926.

1,602,899

UNITED STATES PATENT OFFICE.

WILFRED L. GREENAWAY, OF LOS ANGELES, CALIFORNIA.

REINFORCED TOOL HANDLE.

Application filed December 30, 1925. Serial No. 78,380.

This invention relates to improvements in handles for use in connection with tools, such as hammers, axes, hatchets, and the like, and has for its principal object to provide a means for reenforcing the handle so that the same will be strengthened and will further withstand hard wear without splitting or breaking.

A further object of the invention is to provide a reenforced tool handle wherein the reenforcing means is of such construction as to enable the same to be readily and easily placed in one end of the handle, the handle and reenforcing means therefor being further of such construction as to prevent any possibility of the reenforcing means from becoming accidentally dislodged from the handle.

A further object is to provide a reenforced tool handle of the above mentioned character which is simple in construction, inexpensive, strong and durable and further well adapted to the purpose for which it is designed.

Other objects and advantages of this invention will become apparent during the course of the following description taken in connection with the drawings.

In the accompanying drawing forming a part of this application and in which like numerals designate like parts throughout the same:

Figure 1 is a side elevation of a partly finished wooden handle showing the reenforcing means associated therewith.

Figure 2 is an edge elevation thereof.

Figure 3 is a detail perspective view of the reenforcing means.

Figure 4 is a detail of one of the reenforcing plates.

Figure 5 is a similar detail of the complementary reenforcing plate.

Figure 6 is a fragmentary detail perspective showing a modification of the inner end of the reenforcing means.

Figure 7 is a view similar to Figure 3 illustrating a further modification, and

Figure 8 is a detail perspective view of the auxiliary plate, forming a part of the last mentioned modification.

In the drawing wherein for the purpose of illustration is shown the preferred embodiment of my invention, the numeral 1 designates generally a tool handle which is preferably formed of wood, the end of the handle which is adapted to be disposed in the usual eye or recess provided therefor in the

tool such as the hammer head or hatchet with which the handle is associated, is shown in its unfinished condition, and is indicated at 2 in the drawing. The handle is provided with the intersecting saw cut or slits 3 and 4 respectively, the same extending from the tool end of the handle for a major portion thereof, as is clearly illustrated in Figures 1 and 2. These longitudinally extending intersecting saw cuts or slits which are arranged at substantially right angles to each other have their inner ends rounded as is illustrated at 5, and the purpose thereof will be presently apparent.

The reenforcing means for the tool handle is shown generally at 6 and the same comprises the complementary plates 7 and 8 respectively which are formed of suitable metal. The plate 7 is of such width as to have its side edges extending flush with the edges of the handle 1, the plate 7 being adapted to be disposed within the slit 4 whereas the complementary plate 8 is of such size as to be received in the intersecting slit 3 so that the edges of the plate 8 will lie substantially flush with the outer faces of the sides of the handle. It is also to be understood that these plates are so shaped as to conform to the shape of the handle, the edges of the respective plates will not protrude beyond the edges or outer faces of the sides of the handle.

The plate 7 is provided at its outer end with the longitudinally extending slit 9, whereas the complementary plate 8 has its longitudinally extending slit 10 formed in the inner end thereof. These slits cooperate so as to enable the complementary plates to be interfitted with each other, and be disposed at substantially right angles and by further arranging these slits in the manner above described, the plates comprising the reenforcing means will be interlocked. As is clearly illustrated in Figures 3, 4, and 5, of the drawing, the inner ends of the plates are cut away to provide the concave faces 11 for cooperation with the rounded inner end of the intersecting slits formed in the handle when the reenforcing means is driven into the slotted end of the handle.

When the reenforcing plates are driven into the respective slits provided therefor in the handle 1, suitable means may be provided for securing the same therein such as by using cement, or any other filling composition well known in the art. It is of

course understood that the head 2 of the handle is to be trimmed to accommodate the tool with which the handle is to be associated.

5 In Figure 6 of the drawing the inner ends of the interlocked reenforcing plates are notched, and it is to be understood that the same are to be used when the inner ends of the slits which are formed in the handle 10 for receiving the plates are similarly shaped.

15 In Figure 7 of the drawing, a further modification of the reenforcing means is shown wherein the plate 12 which is similar to the plate 7 heretofore more fully described is provided with the longitudinally extending slits 13 in its forward end, and a relatively short longitudinally extending slit 14 in its opposite end. The complementary plate 15 is somewhat similar to the 20 complementary plate 8, the plate 18 however being of a lesser length than the plate 12, the inner end of the complementary plate 15 being slit longitudinally whereby the plate may be interfitted and interlocked in 25 the same manner as the plates 7 and 8.

30 The outer end of the plate 15 lies substantially flush with the outer end of the right angularly disposed plate 12, but the inner end of the complementary plate 15 terminates at a point adjacent the inner end of the plate 12, and the inner end of the plate 15 is cut away to provide the inwardly tapered portion 16.

35 Cooperating with the slit 14 formed in the inner end of the plate 12 is the slit 17 formed longitudinally in the outer end of the auxiliary plate 18, the outer end of the auxiliary plate 18 being notched as illustrated as at 19 to coact with a tapered end 40 16 of the plate 15, and furthermore the inner end of the auxiliary plate 18 is curved to cooperate with the curved inner end of the plate 12. Thus when the plates 15 and 18 respectively are interfitted and interlocked with the plate 12, the plates 15 and 18 will extend for substantially the same length as the plate 12, and the reenforcing means will be completely assembled. The purpose of the auxiliary plate which acts 45

as a wedge is to strengthen the structure, 50 and also equalize the pressure placed on the handle.

It will thus be seen from the foregoing description that I have provided a tool handle and a reenforcing means therefor, which 55 will be greatly strengthened, and the handle will withstand unusually hard wear without splitting or breaking. Furthermore, the reenforcing means is of such construction as to prevent the accidental dislodgment thereof from the handle, and will furthermore in no way interfere with the grasping of the handle when the tool with which the same is associated is in use.

60 To further afford a greater gripping area 65 as well as tending to prevent the splitting of the handle, spurs such as are shown at 20 in the drawing are formed on the longitudinal side edge of each plate. These spurs are preferably arranged in pairs. Normally 70 the spurs are disposed in the same plane as the respective plate on which they are formed, and after the plates are inserted in the respective slits in the handle, the spurs are bent over in opposite directions, and clinched into the wooden handle, so that a smooth surface will be provided.

75 While I have shown the preferred embodiment of my invention, it is to be understood that minor changes in the size, shape 80 and arrangement of parts may be resorted to without departing from the spirit of the invention, and the scope of the appended claim.

Having thus described the invention, what 85 I claim as new and desire to secure by Letters Patent is:—

80 A tool handle having one end thereof provided with longitudinally extending intersecting slits, reenforcing means for said handle comprising a pair of interlocked plates adapted to be disposed in the respective slits, and spurs formed on the longitudinal edges of each plate and adapted to be bent over and clinched into the handle. 85

90 In testimony whereof I affix my signature.

WILFRED L. GREENAWAY.
